(57) **CLAIM**

The ornamental design for a wand for fusing pipe, as shown and described.

DESCRIPTION

FIG. 1 is a perspective view of the wand for fusing pipe according to the present disclosure.

FIG. 2 is a front view of the wand for fusing pipe according to the present disclosure.

FIG. 3 is a rear view of the wand for fusing pipe according to the present disclosure.

FIG. 4 is a left side view of the wand for fusing pipe according to the present disclosure.

FIG. 5 is a right side view of the wand for fusing pipe according to the present disclosure.

FIG. 6 is a top view of the wand for fusing pipe according to the present disclosure; and,

FIG. 7 is a bottom view of the wand for fusing pipe according to the present disclosure.
